UNITED STATES PATENT OFFICE.

PHILIPPE DELBERT, OF PARIS, FRANCE.

STEERING-BALLOON.

SPECIFICATION forming part of Letters Patent No. 761,062, dated May 31, 1904.

Application filed March 3, 1903. Serial No. 145,881. (No model.)

To all whom it may concern:

Be it known that I, PHILIPPE DELBERT, gentleman, of No. 40 Rue Copernic, Paris, France, have invented a certain new and useful Improved Steering-Balloon; and I do hereby declare the following to be a full, clear, and exact description of the invention, such as will enable others skilled in the art to which it appertains to make and use the same.

10 The invention which is the subject of the present application for a patent refers to a new system for steering a balloon.

15 The essential characteristics of my invention are, first, the special arrangement of a double helix acting as a propeller on a rigid balloon, which turns with its axis or around this latter under the action of the energy transmitted to it from a source in the car, which is suspended in a special manner; second, the arrangement for the suspension of the motors to the rigid envelop carrying the helix or to the axis on which it revolves and also the manner of connecting the motors to the source of energy; third, the arrangement 25 which insures the automatic working of the safety-valves, which are suitably mounted upon the envelop.

My invention is represented in detail on the accompanying drawings.

30 Figures 1 and 1^A show the entire balloon in elevation. Fig. 2 is a detail of a portion of the surface of the rigid envelop in elevation, showing a piece of the double helix which it carries and the way this latter is secured. 35 Fig. 3 is a detail in elevation of a diaphragm for the automatic operation of the safety-valves. Fig. 4 is a detail in elevation, on a larger scale, showing the manner of suspension of one of the motors and the means for 40 directing the axis of the balloon, also the guide of the link of suspension of the car, shown in plan in Fig. 7. Fig. 5 is a section of a detail through C D of Fig. 6. Fig. 6 is a section of a detail through A B of Fig. 4. 45 Fig. 8 is a partial sectional elevation showing the method of driving the rigid envelop in the case in which it turns around its axis, this latter remaining fixed. Figs. 9 and 10 show in partial sectional elevation the details of the 50 arrangement for the automatic operation of the safety-valves, the valves being respectively closed and open.

In the example in Figs. 1 and 1^A the rigid envelop *a* is virtually made in one with the tube *c* and the latter is operated by the motors. The envelop *a*, which has the shape of an ellipsoid of revolution, is preferably made of sheets of aluminium suitably joined together and hooped inside and out. On the surface is secured by angle-pieces *d* and *e*, 55 Fig. 2, a double-surface helix—that is to say, presenting two inclinations at forty-five degrees, or forming, in other words, an angle-iron or **V** reversed. The double helix extends from one pole to the other of the ellipsoid, its pitch being advantageously made equal to the length of the axis between the two poles. It can, if preferred, be made smaller. The helix is at every point on the surface inclined at forty-five degrees to the 60 tangent of the ellipsoid, and it is possible by means of this double helix to effect a movement backward or forward by means of a reversible motor. The axis *c* is adapted to turn in bearings which are shown in detail 65 in Figs. 4, 5, and 6. At each end the bearings are similar. Each consists of a ring *f* of antifriction metal, so shaped that the transverse section consists of two parabolas joined in reversed positions, which reduces the points 70 of contact with the tube to a minimum, and two steel collars *g*, secured to the tube, which inclose laterally the aforesaid ring. This ring is embraced by a steel strap *h*, made in halves suitably fastened together. The 75 width of *f* being greater than that of *h*, *h* does not rub against the collars *g*. The exterior straps *h* serve also to support a semi-circular supporting-bar *i*, which is rigidly secured to the straps *h*. This bar *i* provides, with the assistance of the brackets *j*, 80 a support for the motor *k* and also serves as a path for the rolling and guiding of the head of the suspension-cable *l*. This head consists of a fork *m*, between the branches of 85 which is carried the axis of a roller *n*. The movement of the roller *n* is thus limited by the brackets *j*. The motors *k* transmit to the tube *c* the movement of their shaft *o* by any suitable means of transmission—such as a 90 chain *p*, for example, fitting into two sprocket-wheels *q* and *r*, arranged, respectively, on the shaft and on the tube. The car *s* is carried by a central suspension-rod *t*, to which 95 100

is secured the two cables l , each having a rolling head and which serve also to carry the conductors u , intended to convey the current derived from the generating source v , carried in the car. Two metal wires z , of which one end is fastened to a suitable point in each of the semicircular bars of suspension i , are wound at their other ends on the windlasses y , carried by the car, and permit of an inclination being given to the balloon while the car is maintained in a horizontal position. In effect, as is easy to understand by examining the diagram of Fig. 11, it is sufficient in order to incline the balloon downward on the left to shorten the wire z a certain length z , at the same time lengthening the opposite wire a corresponding length. The car will be displaced from v to v' , moving parallel to itself by means of the connection of the suspension-links, the leading-pulleys l in the plane of the windlass assisting in the preservation of this parallelism. The poles of the envelop a are strengthened by sockets 2 , which are secured to the tube c . The rud-
ders 3 can be attached by hinges onto the suspension-cables l , and their movements may be limited by an abutment-rod 4 . The steering of the car is effected by means of wires 6 and cross-poles 5 . All these arrangements remain to some extent the same in the case when the tube c is fixed and only the envelop a rotates upon the tube. In this case, however, a tube 7 of small thickness, Fig. 8, extends from one pole to the other of the ellipsoid and separates the envelop a from the tube c , forming an air-tight joint. The sockets 2 carry bearings constructed similarly to that of Figs. 5 and 6 and serve at the same time as a support to a mechanism adapted to receive the motive power. This mechanism may be, for example, as shown in Fig. 8, a spur-wheel 8 , to which movement is transmitted by a pinion 9 , fastened to the shaft o of the motor. The envelop a is in all cases provided with one or more manholes 10 , with air-tight covers, for the purposes of construction, filling, and examination.

The arrangement for the automatic operating of the valves 11 is shown in dotted lines on the elevation of the whole in Figs. 1 and 1^A and in detail in Figs. 9 and 10. Flexible diaphragms 14 , such as are represented in elevation in Fig. 3, are provided arranged in planes normal to the axis of the ellipsoid passing through the foci. The exterior circumference of these diaphragms is fastened to an interior hoop 12 of the envelop, while the central part of the diaphragm is secured to a sleeve 13 , movable on the tube c . This sleeve is itself fastened by the wires 16 and 17 to bell-crank levers 18 , connected to each of the valves. These bell-cranks are pivoted on brackets 19 . The valves, attached by hinges to the envelop, open outward and are normally held closed by springs 20 . Under the influence of an in-

terior expansion the diaphragms 14 tend to move away from the center toward the poles, (in the direction of the arrow 15 in the case of the diaphragm shown in Figs. 9 and 10,) and each bell-crank 18 will be pulled at the same time by a wire 16 and a wire 17 . Each valve will be thus lifted by the simultaneous movement of two opposite diaphragms.

It is apparent that the tubes c of two balloons such as I have just described can be coupled, if desired, and by means of transverse shafts, supported by the coupled tubes, have communicated to them a movement derived from a single motor carried by an intermediate car, the weight of which is supported equally by the two envelops.

I claim—

1. In combination in a balloon, a rigid envelop, axles supporting the same, semicircular bars suspended from the axles, a car, and means for suspending the car from the semicircular bars, said means having movement thereon, substantially as described.

2. In a balloon, a rigid envelop, a helix thereon, axles supporting the same, bearings on the said axles, semicircular bars suspended from the bearings, means for rotating the balloon carried by the semicircular bars, a car, and connections from the car to the semicircular bars, said connections having movement on the bars.

3. In a balloon, an axle for the same, bearings on the axle, semicircular bars suspended from the bearings, rollers carried on the bars and having movement thereon, suspending-cables attached to the rollers and a car supported by the said cables.

4. In a balloon, a rigid envelop, a helix thereon, axles supporting the same, bearings on the said axles, semicircular bars suspended from the bearings, means for rotating the balloon carried by the semicircular bars, a car, adjustable connections from the car to the semicircular bars, and connections from the car to the bars for inclining the balloon.

5. In combination in a balloon, an axle supporting the same, safety-valves in the balloon and means for automatically operating the said valves, consisting of a flexible diaphragm, a sleeve movable on the axle, a hoop connected to the interior of the envelop, said diaphragm having its periphery and center connected with the said sleeve and hoop, a bell-crank connected to the valve and a connection from the sleeve to the said bell-crank whereby when the diaphragm is moved outwardly the bell-crank will, through the said connection, open the valve.

In testimony whereof I have hereunto set my hand in the presence of two subscribing witnesses.

PHILIPPE DELBERT.
